UNITED STATES PATENT OFFICE

150,822

DESIGN FOR A NURSERY BED UNIT

Arthur M. Bleich, Cambridge, Ohio

Application October 21, 1946, Serial No. 134,136

Term of patent 14 years

(Cl. D5—5)

To all whom it may concern:

Be it known that I, Arthur M. Bleich, a citizen of the United States, residing at Cambridge, in the county of Guernsey and State of Ohio, have invented a new, original, and ornamental Design for a Nursery Bed Unit, of which the following is a specification, reference being had to the accompanying drawings, forming a part thereof.

In the accompanying drawings:

Figure 1 is a perspective elevational view of a nursery bed unit, illustrating the new design;

Figure 2 is a top plan view of the device illustrated in Figure 1;

Figure 3 is a front elevational view of the device illustrated in Figure 1;

Figure 4 is a rear elevational view of the device illustrated in Figure 1;

Figure 5 is an end elevational view of the device illustrated in Figure 1.

I claim:

The ornamental design for nursery bed unit, substantially as shown.

ARTHUR M. BLEICH.
